(57) **CLAIM**

The ornamental design for a vehicle front fender, as shown and described.

DESCRIPTION

FIG. 1 is a front perspective view of a vehicle front fender showing our new design;

FIG. 2 is a rear perspective view thereof;

FIG. 3 is a side view thereof, the opposite side being a mirror image thereof;

FIG. 4 is a rear view thereof;

FIG. 5 is a front view thereof;

FIG. 6 is a top view thereof; and,

FIG. 7 is a bottom view thereof.

It will be understood that the broken lines presented in the drawings are for illustration only, and do not form a part of the claimed design.

1 Claim, 5 Drawing Sheets
